UNITED STATES PATENT OFFICE.

GEORGE W. COPE AND WILLIAM L. BERTRAM, OF DETROIT, MICHIGAN,
ASSIGNORS TO C. EMRICH, OF COLUMBUS, OHIO.

DESIGN FOR A COOK-STOVE.

SPECIFICATION forming part of Design No. 27,667, dated September 21, 1897.

Application filed August 11, 1897. Serial No. 647,927. Term of patent 7 years.

To all whom it may concern:

Be it known that we, GEORGE W. COPE and WILLIAM L. BERTRAM, citizens of the United States, residing at Detroit, in the county of Wayne and State of Michigan, have invented and produced a new and original Design for Cook-Stoves, of which the following is a specification, reference being had therein to the accompanying drawing.

10 The leading feature of the design is the ornamentation.

The legs have the plain curved front A and a marginal scroll ornament which extends up to the skirt.

15 The skirt ornament comprises a middle irregularly-shaped oval panel B, surrounded by a rococo scroll C, and at either end of the ornament is a scroll-shaped shell ornament D. E is a plain base.

20 The oven-door has a large central ornament comprising radial panels and having outwardly-curved edges, ornamented. Surrounding this central ornament is a rococo scroll ornamentation, as shown.

25 The water-tank end ornamentation comprises a substantially circular plain swell panel G, surrounded by a scroll H, as shown, being formed by a scroll ornament F, which

merges into or extends from the marginal scroll of this panel.

30 The fire-door has a similar central panel G', with surrounding ornamentation, as shown, and below the fire-door is similar ornamentation H'.

The ash-chamber is ornamented, as shown 35 at I, by a rococo marginal ornament around a plain space or panels, and the front is ornamented in similar style, as shown.

What we claim as our invention is—

1. In a cook-stove the design for oven-door 40 substantially as herein described and shown.

2. In a cook-stove, the design for water-tank, substantially as herein described and shown.

3. In a cook-stove the design for skirt, sub- 45 stantially as herein described and shown.

4. The design for cook-stove herein described and shown.

In testimony whereof we affix our signatures in presence of two witnesses.

GEORGE W. COPE.
WILLIAM L. BERTRAM.
